RIBBON LOOM

William Harris, Paterson, N. J.

Application June 26, 1939, Serial No. 281,113

6 Claims. (Cl. 139—138)

In a well-known type of loom, as a ribbon loom, a rack reciprocatory lengthwise of and in the back-and-forth-movable batten drives the shuttles, as through pinions. A system to transmit reciprocation to the rack includes flexible connections, as straps, and a rotary guiding means housed within with its axis substantially horizontal and crossing the batten and up to which said connections extend and around which 5 in opposite directions they then extend and exist attached to the rack. Suitable means, removed from the batten, as a suitably and constantly rotated double-crank to which the connections are respectively connected at opposite sides of 10 its axis of rotation, imparts pulls to said connections independently of each other and in alternation, that is to say, so that a pull is exerted on one connection or the other each time the batten structure is back and the warp sheds 15 20 open to receive the shuttles.

The construction is such that, since said connections reach up into the space in the batten in which said guiding means is located and since said space is necessarily of limited width and 25 taking into account the back and forth movements of the batten relatively to a guide for said connections having fixed location, as on the floor near the lay-swords for supporting the batten, the connections in their own back and forth 30 travel wipe against the batten and so become chafed and sooner or later cease to be any longer serviceable and have to be replaced by new ones.

The object of this invention is so to improve the construction of a loom of this type as to 35 eliminate all contact of the lengthwise traveling connections with any relatively fixed part of the batten structure and the consequent wear thereof.

In the drawing:

Fig. 1 is a side elevation of so much of the 40 improved loom as is necessary for the purpose of illustrating the invention;

Fig. 2 is a front elevation, partly in section, of that end of the batten structure to which the invention is applied, showing certain parts 45 present in accordance with the invention; and

Fig. 3 shows the rack and said guiding means in section and portions of said connections in elevation.

The batten structure includes, as usual, the 50 batten 1, supported by lay-swords 1a so as to be movable forward or to the right and back, and a top rail 2 parallel with the batten and which is supported by end walls, such as 3, and by the usual spaced blocks, not shown, in the grooves 55 of which the shuttles are guided and move.

In grooves 4 in the batten and rail is reciprocatory the rack which here comprises racks proper 5 in the respective grooves and lapped plates 6 secured to the respective racks proper and held together by a clamp 7 and screws 1a. 5

The mentioned system, including the rotary guiding means and the flexible connections, is as follows: A cylinder 8 free to rotate around an axis substantially horizontal and crossing said batten structure here constitutes said guiding 10 means; it is journaled on a shaft 9 fixed in brackets 10 which are themselves fixed to the front and back faces of and upstand from the batten, said shaft and brackets thus forming parts of the batten structure. Straps 11 constitute the said flexible connections. They extend in an up-and-down direction (here downwardly) to said guiding means and then around the same in opposite directions and exist attached to the 15 rack, as at 11a.

Means is provided to maintain the connections clear of the batten structure between the medium (to be referred to) which exerts pulls on them and the guiding means 8, thereby to eliminate wear of the connections as they travel 20 lengthwise in response to such pulls and also partake in the back and forth movements of said structure, as follows: A pair of independently rotative members is indicated at 13, each having its axis extending lengthwise of the rack and 25 hence crossing the axis of the guiding means 8. For supporting these members the batten structure includes brackets 14 affixed to the back of the batten and upstanding above rail 2 and affixed to the brackets at 15 a shaft 16 on which 30 said members are directly journaled, the latter being confined against axial displacement in any way, as by collars 17 fast to the shaft. The said members are of such diameter as to project forwardly beyond the rail 2 and rearwardly well 35 beyond the back of the batten structure.

The connections extend up behind the batten structure, then in bights or bends over said members 13 and then down to guiding means 8.

The medium for exerting pulls on said connections independently of each other and alternately may be of well-known type, say consisting of the usual double-crank 18 to diametrically opposite points of which the ends of the connections are attached, the same being suitably journaled and rotated constantly substantially as in the patent to Sands, No. 1,138,418. 20 is suitable guiding means, as rollers journaled in a stand 21 fixed to the floor near the lay-swords, 55

around which, between the double-crank and the members 13, the connections extend.

So as not to chafe or override each other the portions of the connections which reach from said members 13 to the guiding means 8 should extend around the latter in different upright planes. Hence the construction is such that one member reaches further than the other crosswise of the rack, as shown in Fig. 1; said members being here journaled on a common axis, one is for this purpose formed of greater diameter than the other.

As will be evident, my construction avoids all contact of the connections 11 with relatively fixed parts as they travel in response to the pulls exerted thereon and partake of the back and forth movements of the batten structure, and it is also such as to avoid the straps overriding or chafing each other.

20 I do not wish to be limited to the precise construction herein shown, what I claim being:

1. In a loom of the class described, the combination of a back-and-forth-movable batten structure, a shuttle-driving rack reciprocatory therein lengthwise thereof, a system to transmit reciprocation to the rack including flexible connections and a rotary guiding means journaled in said structure with its axis substantially horizontal and crossing said structure and to which means said connections extend in an up-and-down direction and around which they then extend and exist attached to the rack, means, removed from said structure, to exert pulls on said connections independently of each other and alternately, and means to maintain said connections clear of said structure between the last-named means and said rotary means including two independently rotative members journaled each on an axis extending lengthwise of the rack and in peripheral engagement with which, respectively, said connections extend, one member reaching further than the other in one hori-

zontal direction crosswise of the rack, whereby the portions of said connections which reach from said members to said guiding means extend around the latter in different upright planes.

2. The combination set forth in claim 1 characterized by said members being journaled on a common axis.

3. The combination set forth in claim 1 characterized by said members being journaled on a common axis and being of different diameters.

4. In a loom of the class described, the combination of a back-and-forth-movable batten structure, a train of parts movable back and forth in said structure including a rack confined thereto to move lengthwise thereof and rotary means journaled in said structure with its axis crosswise thereof and substantially horizontal, flexible connections extending in an up and down direction to and in opposite directions around said rotary means and connected to a part of 20 said train, means, removed from said structure, to exert pull on the connections independently of each other and alternately, and means to maintain said connections clear of said structure between the last-named means and said rotary 25 means including two independently rotative members journaled each on an axis extending lengthwise of the rack and in peripheral engagement with which, respectively, said connections extend, one member reaching further than the 30 other in one horizontal direction crosswise of the rack, whereby the portions of said connections which reach from said members to said guiding means extend around the latter in different upright planes.

35 5. The combination set forth in claim 4 characterized by said members being journaled on a common axis.

6. The combination set forth in claim 4 characterized by said members being journaled on a 40 common axis and being of different diameters.

WILLIAM HARRIS.
